UNITED STATES PATENT OFFICE.

JOHN B. EDWARDS, OF NEW YORK, N. Y.

CLOTH-CUTTER.

1,191,164.

Specification of Letters Patent. Patented July 18, 1916.

Application filed March 8, 1915. Serial No. 13,025.

To all whom it may concern:

Be it known that I, JOHN B. EDWARDS, a citizen of the United States, residing at New York city, county and State of New York, 5 have invented certain new and useful Improvements in Cloth-Cutters, of which the following is a full, clear, and exact specification.

This invention relates to cloth cutters of 10 the class in which a motor driven circular cutter disk is mounted on a platform or base to be advanced by hand during the cutting operation.

One object of the present invention is to 15 prevent the fingers of the operator from being cut by contact with the circular blade, which often occurs with the cutters now generally in use.

Another object is to provide improved 20 means for sharpening the knife when the cutter is not being used for cutting cloth, and in order to insure against injury to the operator while the sharpening is being effected, I provide means for automatically 25 locking the machine against being advanced along the cloth during the sharpening operation.

A further object is to provide means for 30 steadyng the machine with the left hand as it is being advanced along the cloth with the right hand in the usual manner, and for keeping the cloth from waving.

Considerable use will necessarily wear 35 down the circular cutting blade and after a while the space between the cutting edge and the base or platform of the machine will become so great that the cloth will not be properly cut, and it has been necessary in prior machines to then discard the knife 40 and substitute a new one.

It is also the object of this invention to 45 avoid the necessity of throwing away the old knife when worn down as described, by providing means for taking up the space between the cutting edge and base of the machine and presenting the cloth to the worn blade so that the cutting will be accomplished as effectively as by a new blade.

The invention will be first hereinafter 50 described in connection with the accompanying drawings, which constitute a part of this specification, and then more specifically defined in the claims at the end of the description.

55 In the accompanying drawings, wherein

similar reference characters are used to designate corresponding parts throughout the several views:—Figure 1 is a side elevation of a cloth cutter constructed in accordance with my invention, the same being shown in 60 position for sharpening or grinding the blade. Fig. 2 is a detailed side view of blade and guard showing the normal overlapping position of the latter when the machine is in use for cutting cloth. Fig. 3 is a detailed 65 side view of the adjustable block for taking up wear on the blade. Fig. 4 is a plan view of the same. Fig. 5 is a front elevation of the cutting machine, the parts being in the same positions as in Fig. 1. Fig. 6 is an internal plan view of the motor casing with the motor removed, showing more particularly the sliding operating member for depressing the grinders into position to contact with the blade. Fig. 7 is a detailed plan 75 view of said operating member. Fig. 8 is a plan view of the base or platform of the machine. Fig. 9 is a detailed side view of the knife guard. Fig. 10 is a front edge view of the same. Fig. 11 is a broken front 80 elevation of the lower part of the machine, showing more particularly the driving connection between the motor shaft and circular knife. Fig. 12 is a detailed view of the grinder, partly in section. Fig. 13 is an end 85 view of one of the holding devices for the grinders, and Fig. 14 is a section on the line $\alpha-\alpha$ of Fig. 12.

Referring to the drawings, 1 designates the base or platform of the machine, which 90 is flat on the bottom and curved at the edge in order to guide the cloth up over the same during the cutting operation. The circular blade or knife 2 is mounted on one side of a standard 3 which rises from the base 1 95 and supports on its upper end a casing 4 for the usual electric motor (not shown). As shown in Fig. 1, the blade may be mounted on ball bearings 5, and as best illustrated in Fig. 11, said blade is formed with a beveled pinion 6 which meshes with a beveled pinion 7 on the motor shaft 8.

Extending rearwardly from a point just below the casing 4 is a handle 9 having a collar 10. Below the handle, that is, below 105 the portion thereof which extends under the casing 4, there is a tubular member 11, angular in cross section and having a horizontal slot 12 in its side. Within said tubular member 11 there is arranged a block 13 110

which is pressed forwardly by a coiled spring 14 also housed in the tubular member. The block 13 is connected to a bracket 15 depending on the outside of the tubular member 11 and supporting an arcuate guard 16 which lies adjacent the beveled edge or face of the blade. When the machine is being used for cutting cloth, the guard is arranged as shown in Fig. 2, so as to overlie the cutting edge of the blade and thus prevent the fingers of the operator from coming in contact with said edge. When the guard is in this position, the block 13 is advanced owing to the spring 14. The guard, however, may be moved rearwardly, so as to expose the cutting edge of the blade for grinding the same, as will be hereinafter explained, by means of a rearwardly projecting arm 17 attached to the bracket 15 and having a knob 18 on its end adapted to engage the collar 10 on the handle for holding the guard in its retracted position, as illustrated in Fig. 1.

The sharpener or grinder comprises a pair of facing stones or blocks of grinding material 19, and 20 mounted on a swinging frame 21 pivoted to the front end of the machine preferably near the bottom of the casing 4. The frame 21 is pivoted in such a manner as to swing in a vertical plane so as to bring the grinding stones 19 and 20 on either side of the knife during the grinding operation. The grinder is normally held away from the blade, by a spring 22 fastened at one end to the casing 4 above the pivot of the grinder, and secured at its other end to an inclined lever 23 rigidly attached to the frame 21. In Fig. 1 the grinder is shown in operative position engaging the blade, as when the arm 23 is pressed down by the operator. For depressing the grinder and bringing it in position for sharpening the knife, I provide a sliding member 24, see Figs. 1, 6 and 7. This sliding member passes through the bottom of the casing 4 and has a loop 25 passing around the driving shaft 8. One end of this member projects from the rear of the casing 4 and is provided with a thumb piece 26 for operating the same. The other end of the member 24 projects from the front of the casing 4 and is forked, as at 27, to engage the lever arm 23. It is obvious that when the member 24 is pushed forward by placing the thumb on the end piece 26, the forked end 27 will ride along the inclined portion of the lever arm 23 and depress the frame 21 carrying the grinder. It will also be noted that before the grinding stones can come in contact with the edge of the knife for sharpening the same, the guard 16 must be withdrawn or moved rearwardly to the position shown in Fig. 1. In other words, when the guard is in its advanced position, as illustrated in Fig. 2, which position it occupies when the cutting machine is in operation, it is im-

possible to sharpen the blade, and in order to perform the sharpening operation it is necessary for the operator to withdraw the guard by a separate action which will serve to notify him that the blade is exposed. 70

As a further precaution against cutting the fingers while the guard is withdrawn and the grinder is in operative position, I provide a pivoted device on the lower end of the guard for automatically locking the 75 machine against movement along the cloth while the blade is being sharpened. As best illustrated in Figs. 1, 9 and 10, said device is pivoted at 28 and has a downwardly inclined pointed arm or pin 29, and an upwardly inclined operating arm 30, a portion of which is curved substantially as shown. The locking device is normally held with the point of the pin 29 out of contact with the cloth by means of a spring 31 fastened 80 at one end to the guard above the pivot 28, and secured at its other end to the arm 30. A depending part 32, which is rigidly fastened to the frame 21 of the sharpener, extends into the path of the curved portion of the arm 30, so that when the sharpener is depressed into operating position, said part 32 will act upon the arm 30 to throw the pin 29 down into engagement with the cloth and thus prevent the machine from moving along 85 the cloth and the cutting operation being continued until after the sharpening has been finished and the grinder permitted to swing upward away from the blade, by removing the thumb from the button 26 on 90 the end of the member 24. As soon as the grinder frame 21 with its depending part 32, swings upward to this position, the spring 31 will raise the pin or pointed arm 29 to the position illustrated in Fig. 9, where 95 it will not interfere with the movement of the cutter along the cloth. 100

In the use of machines of this kind it has been found that it is sometimes difficult to properly steady the device with the single hand which grips the handle, and to prevent the cloth from working up in waves. I have, therefore, provided means whereby the other hand may also be used to assist in steadyng the machine in operation. For this purpose, 110 I have illustrated two finger pieces 33 on the side of the machine which faces the operator, but it will be understood that more or less of these finger pieces may be used if desired. Each of the finger pieces 33 consists of a vertical extensible portion 34 and a horizontal part 35 to receive the finger. The extensible portion 34 may be made in two pieces overlapping and connected adjustably to each other by a thumb screw 36 115 fastened to one piece and passed through a slot 37 in the other piece. The portion 34 preferably extends up into a tubular casing 38 and is provided with a head 39 on its upper end, below which head a coiled spring 120 125 130

40 is placed for normally supporting the finger piece and adapting the same to yield under the pressure of the operator's fingers.

Referring again to the grinder, the frame 5 21 is provided at its lower ends with angular 21 passageways 41 in which are fitted correspondingly shaped plugs 42, and through the plugs screws 43 are passed for rigidly connecting the stones 19 and 20, respectively, to 10 said plugs 42. A washer or cap plate 44 is held to the outer end of each of the plugs by the screw 43 and projects beyond the plug at one side, as at 45, see Figs. 12 and 13. A small screw 45^a is passed through the projecting portion 45 of the washer 44 and engages the side of the frame 21 for holding the stone firmly against the inner face of the frame. One stone, 20, is arranged obliquely with respect to the frame 21, for 20 the purpose of grinding the beveled face of the cutting edge of the blade, while the other stone, 19, preferably has its working face arranged parallel to the sides of the frame so that it may engage the flat face of 25 the cutting edge of the blade and remove any bur which may be formed by grinding the beveled face of said cutting edge.

In order to avoid the necessity of discarding an old blade when it has become worn down so as not to properly engage the cloth as it passes over the base 1, I have provided an adjustable block 46, see Figs. 1, 3 and 4. This block is mounted on the base in advance of the cutting edge of the knife and 35 has its front edge curved, as at 47, for guiding the cloth over said block to the knife. The front end of this block is secured to the base by two screws 48, one engaging each of a pair of ears on the sides of the block near 40 its front end. The rear end of the block is adjustable vertically on the base 49 by means of a screw 50 threaded in the block and having its lower end seated in a smooth socket in the base 1. By loosening the front screws 45 48, and turning the screw 50 inward, the rear end of the block 46 will be raised so as to bring the cloth up against the cutting edge of the knife. After the desired adjustment of the plate 46 has been attained, the screws 50 48 may be tightened, whereupon the block 46 will be held rigidly in position.

Having thus described my invention, what I claim is new and desire to secure by Letters Patent of the United States is:

55 1. In a cloth cutter of the character described, the combination with a circular blade, of an arcuate guard for the edge of the blade, resilient means for normally holding the guard in position to protect the edge 60 of the blade, a finger piece for moving said guard away from the cutting edge, and

means on the end of said finger piece for locking the guard in its restricted position.

2. In a cloth cutter of the character described, the combination with a circular 65 blade, of a handle, a collar on the handle, an arcuate guard for the edge of the blade, resilient means for normally holding the guard in a position to protect the cutting edge, and an arm attached to the guard and 70 having a knob on its end to engage the collar on the handle for holding the guard in retracted position.

3. In a cloth cutter of the character described, the combination with a circular 75 blade, of an arcuate guard for protecting the edge of the blade, a stationary tubular casing having a horizontal slot, a block fitted to slide in said casing and connected to the guard, a spring in the casing engaging 80 the block for normally holding the guard in position to protect the cutting edge, and an arm for retracting the guard.

4. In a cloth cutter of the character described, the combination with a circular 85 blade, of a grinder movable to and from the edge of the blade, and means for automatically locking the machine from cutting cloth while the grinder is in engagement with the cutting edge.

90 5. In a cloth cutter of the character described, the combination with a circular blade, of a guard for protecting the cutting edge, a grinder movable into and out of engagement with said cutting edge, and means 95 mounted on the guard for automatically locking the machine against cutting cloth when the grinder is in engagement with the cutting edge.

100 6. In a cloth cutter of the character described, the combination with a circular blade, of a guard for protecting the cutting edge, a locking member pivoted on the guard and having a pointed arm adapted to engage the cloth and prevent movement of the 105 cutter along the same, means for normally holding the locking device in position where the pointed arm will be out of engagement with the cloth, a grinder movable into and out of engagement with the cutting edge, 110 and means on the grinder for automatically moving the locking device to bring the pointed arm into engagement with the cloth when the grinder is moved into engagement with the cutting edge.

115 In testimony whereof I have signed my name to this specification in the presence of two attesting witnesses.

JOHN B. EDWARDS.
